UNITED STATES PATENT OFFICE.

GEORGE EVANS, OF EL PASO, TEXAS, ASSIGNOR TO EL PASO SASH AND DOOR COMPANY,
OF EL PASO, TEXAS.

BUILT-IN TELEPHONE CABINET.

Application filed September 8, 1926. Serial No. 134,208.

This invention relates to a telephone cabinet which is intended to be built-in to the room of a dwelling when constructed and is adapted to provide a shelf for the battery and call bell which is normally substantially closed, a shelf for the telephone which is mainly open, and a lower compartment normally closed which may contain a directory and can be swung to open position to furnish a shelf of lower level upon which the telephone may be placed. The whole cabinet may be constructed of wood and finished in accordance with the rest of the interior wood work of the room in which it is placed.

In the drawings:

Figure 1 is a front view of the cabinet.
Figure 2 is a vertical section through the same.

Figure 3 is a cross section on the line 3—3 of Figure 1.

The two spaced walls of the room are indicated at A and B, and timbers C are disclosed which space the walls A and B and 25 between which is located the cabinet.

The cabinet proper is formed of a back wall 1 and side walls 2 and is separated into three compartments by division members 3 and 4 and has a floor 5. The front thereof 30 is formed by a panel 6 having openings cut out for admission to the various compartments, which panel may be surrounded by an ornamentally trimmed member 7. The front of the cabinet projects slightly from the wall B and actual relation between these parts may be varied to attain the desired appearance.

The intermediate division member 4 is projected as shown at 8 and is supported 40 near its center by a small bracket member 9. These parts, of course, may be of any desired ornamental appearance to match the trim of the wood work and the remaining portions of the cabinet.

The upper compartment is designed to contain the call bell and battery and has a closed front 11 provided with perforations arranged in an ornamental panel through 45 which the sound of the bell may easily escape. The intermediate compartment 12 is open and may have an ornamental portion 13 partially closing the upper part of the front of this compartment. The telephone D is intended to be placed in this com-

partment and rest upon the division member 4 and shelf 8.

In the lower compartment is mounted a box like member 14 which constitutes a door 15 hinged to the lower part 6 of the cabinet by hinges 17 and provided with an ornamental panel 16 and a knob 17 for opening and closing the same. This box member is open at the top when it is within the compartment or at the front end when in the dotted line position of Figure 2, and is designed to contain a telephone directory, memorandum pads or the like. The rear wall 19 becomes the top when the member is swung to open position and furnishes a support for the telephone D upon which it 70 may be placed and used by anyone sitting in a chair. The bottom 20 of this box like members rests upon the floor 5 of the cabinet when in closed position.

Hinged at 21 to the sides 2 are links 22 which are hinged at 23 to other links 24 which have their free ends pivoted at 25 to the sides of the box like member 14. When the member 14 is in closed position, these links fold as indicated in Figure 2, but when 80 it is opened the pivot 23 swings outwardly and downwardly until the links 22 and 24 take a straight line position. These two links may be provided with engaging members which will prevent any further swing- 85 ing movement in this direction.

It is obvious that the invention provides a simple and compact cabinet which may be built-in to the wall of any room as the dwelling is constructed or thereafter and 90 which will provide an ornamental appearance. The telephone may be used by a person standing while the same rests upon the shelf formed by the division 4 and extension 8. If the user is seated, the box like 95 member or bin 14 may be swung to open position and the telephone placed thereon. The directory and suitable scratch pads or memoranda may be kept hidden when not in use. The general finish of the cabinet 100 may be varied to conform with the wood work of the room in which it is placed and its ornamental features may be varied widely without departing from the invention. Details of construction may be 105 changed and in general the invention is to be regarded as limited only by the scope of the appended claims.

I claim as my invention:

1. A built-in telephone cabinet comprising a casing adapted to be set into the wall of a room and means dividing said casing into three compartments arranged one above the other, the upper compartment adapted to contain the bell, the intermediate compartment adapted to receive the telephone, and the lower compartment receiving a bin like member which is hinged at its lower end to the front of the casing and swings to open position to permit access thereto and to provide a support for the telephone.
- 10 2. A built-in telephone cabinet comprising

a casing adapted to be set into the wall of a room and means dividing the casing into a plurality of compartments arranged one above the other, the upper compartment having a generally open front and adapted to receive the telephone, and the lower compartment receiving a bin like member which is hinged at its lower end to the front of the casing and swings to open position to permit access thereto and to provide a support for the telephone.

In testimony whereof, I have hereunto subscribed my name.

GEORGE EVANS.
